UNITED STATES PATENT OFFICE.

THOMAS B. ATTERBURY, OF PITTSBURG, PENNSYLVANIA.

DESIGN FOR A DISH.

SPECIFICATION forming part of Design No. 17,192, dated March 15, 1887.

Application filed February 3, 1887. Serial No. 226,469. Term of patent 7 years.

To all whom it may concern:

Be it known that I, THOMAS B. ATTERBURY, of Pittsburg, in the county of Allegheny and State of Pennsylvania, have invented a new and original Design for a Dish; and I do hereby declare the following to be a full, clear, and exact description thereof.

The accompanying drawing is a side view of a covered dish representing a duck in a sitting or crouching position.

The leading feature of the design consists in a dish whose body conforms in configuration to that of a crouching or sitting duck, which is divided horizontally into two parts, the upper part forming the cover.

In the drawing, *a* is the lower part of the

dish, and represents the lower portion of the duck. *b* is the dish-cover, and represents the head and upper part of the duck, the division being on the line *x x*. 20

I claim—

A design for a dish having the body *a* and cover *b*, the whole representing the conventional configuration or shape of a duck in a sitting or crouching posture, substantially as shown and described. 25

In testimony whereof I have hereunto set my hand this 31st day of January, A. D. 1887.

THOMAS B. ATTERBURY.
